UNITED STATES PATENT OFFICE.

CARL WILLERS, OF CHICAGO, ILLINOIS.

ADJUSTABLE HANGER.

Application filed February 6, 1922, Serial No. 534,465. Renewed October 31, 1923.

To all whom it may concern:

Be it known that I, CARL WILLERS, a subject of the King of Sweden, and a resident of Chicago, county of Cook, and State of Illinois, have invented certain new and useful Improvements in Adjustable Hangers, of which the following is a specification:

My invention relates to adjustable shaft hangers, and has for its object improvements in said devices.

In the accompanying drawings—

Fig. 1 is a side elevation of a hanger for a countershaft;

Fig. 2 is an elevation in the direction 2 of Fig. 1;

Fig. 3 is a longitudinal section of the bearing and a part of the hanger frame;

Fig. 4 is a section on line 4—4 of Fig. 3;

Fig. 5 is a side elevation of a modified form of hanger; and

Fig. 6 is a front elevation of the same.

The frame 11 is provided with feet 12 by which it is secured in place in the ordinary manner. The frame 11 is provided with an inclined slot 13, the width of which is a trifle more than the outside diameter of the bearing 14 carried by the hanger. At the upper side of this slot the frame has a tongue 15 which projects into a groove in the bearing as shown in Figs. 1, 3 and 4. This tongue terminates at a point 16 so that when the bearing is moved upward in the slot to its highest point it may be withdrawn laterally from the hanger.

The part 17 of the frame 11 which is below the slot 13, is slotted in a plane perpendicular to that of slot 13, and in this last named slot is a ratchet bar 18 pivoted at 19 to the frame. A spring 20 connected between pin 21 on the frame and pin 22 on the ratchet bar serves to hold said bar normally in the position shown in full lines in Fig. 1. A cord or rod 23 provided with a handle 24 serves as a means for moving the bar 18 to the dotted line position.

The central part of the bearing 14, which is opposite the groove arranged to receive the tongue 15, is provided with teeth 25 which match the teeth on the bar 18. This side of the bearing is flat and bears against the part 17 so as to restrain the bearing from turning on its axis.

When the bearing is in the position shown in Fig. 1, it may be pushed upward by hand in the slot 13. In a case of this kind, the spring 20 yields to permit such upward

movement and acts to hold the ratchet bar so as to prevent a downward movement. By pulling on the cord 23, however, the ratchet bar is freed from the ratchet teeth 60 on the bearing, and said bearing, slides downward in slot 13 by gravity or belt pull.

On the shaft 26 are the ordinary pulleys 27. The belt 28 extends from the counter-shaft to the main drive shaft, and belt 29 65 extends to the machine to be driven. It will be evident that moving the shaft 26 upward along the incline represented by slot 13 serves to tighten both belts at the same time. If the bearings of the countershaft 70 are at their lowest position when the belts 28 and 29 are first put on, adjustments upward of the shaft will serve to take up slack 75 for quite a while before it is necessary to tighten the belts by cutting out a piece and replacing them. And when it does become necessary to shorten the belts, the shaft may be dropped to its lowest position, and long pieces of belt may be taken out instead of short pieces.

Also, if an accident occurs at the machine being driven, that machine may be instantly stopped by pulling the cord 23 and permitting the shaft 26 to move to its lowest position. In such a case, the gravity 85 of the shaft and pulleys is assisted by the pull of the belts 28 and 29.

On each bearing is an arm 30 secured in place by a set screw 31. On the outer ends of such arms is carried by the ordinary belt 90 shifter 32.

In the form shown in Fig. 5, the frame 11 is not in one piece with the feet 12, but said feet are on a bracket 33 having thereon a hub 34. On the frame 11 is another bracket 35 95 having a corresponding hub 36. A bolt 37 passing through both hubs and provided with a nut 38 serves to secure the two hubs together, and consequently the frame 11 to the feet 12. The faces of the hub where they come 100 together are provided with teeth 39 so that when the nut 38 is tightened there is no tendency for the frame 11 to slip with respect to the bracket 33.

In Fig. 1 the line of adjustability of the shaft is fixed at 45 degrees or thereabouts, and any adjustment of the shaft tightens both belts to the same extent. In Fig. 5, the drawing shows the line of adjustability as also at 45 degrees, but it will be evident that 110 by loosening the nut 38 and moving the frame on the pivot 37, the angle of this line

may be made more or less as desired. The essential difference between Fig. 1 and Fig. 5 is that one of them has a fixed line of adjustability whereas the other has a variable 5 line of adjustability. By shifting the line of adjustability from 45 degrees to some other angle, a given amount of adjustment will tighten one belt more than the other.

What I claim is:

- 10 1. A hanger having an inclined slot therein and a second slot perpendicular to the first slot, a bearing located in the first slot and movable longitudinally therein, said bearing having teeth adjacent to the second slot, and 15 a ratchet bar pivoted in the second slot and engaging the teeth of the bearing.
- 20 2. A hanger having two slots therein perpendicular to each other, a bearing adjustably supported in one of said slots, and a pivoted bar located in the other of said slots and serving to retain said bearing at any desired adjustment.
- 25 3. A bearing, a hanger having an inclined slot therein, said slot being so arranged that the bearing may be inserted therein at the upper end thereof and then be moved downward therein, an interlocking connection between hanger and bearing so arranged as to prevent the displacement of the bearing from the slot at any other position than at the upper end of said slot, and releasable holding devices arranged to retain the bearing at any intermediate position in said slot.
- 30 4. A hanger having an inclined slot therein, a bearing in said slot and under strain to move downward therein, said bearing having teeth on the side which engages the hanger at the lower side of the slot, a ratchet

bar located within the body of the hanger and engaging the teeth on the bearing, and 40 a manually operated device for releasing said bar from said teeth.

5. A hanger having a slot therein, a bearing arranged to slide in said slot and having a series of teeth on one side, a bar secured to the hanger and having a longer series of teeth than the series on the bearing, a spring acting to hold the teeth of the bar in engagement with the teeth of the bearing, and a manually operated connection for releasing 50 the bar from the bearing, said parts being so constructed that at any position of the bearing a series of teeth on the bearing engages a series of teeth on the bar.

6. A hanger having an inclined slot, a bearing located in said slot and under strain to move downward therein, a ratchet device pivoted to the hanger, a spring acting upon the ratchet device to cause it to restrain the downward movement of the bearing, and a 60 connection for releasing the ratchet device.

7. A bearing having a groove on one side and ratchet teeth on the other, a hanger having an inclined slot arranged to receive the bearing and the hanger having a tongue projecting into the groove to prevent the displacement of the bearing, a ratchet bar pivoted to the hanger, a spring acting to press the teeth of the bar into engagement with the teeth of the bearing, said parts being so arranged as to restrain the downward movement of the bearing but to permit its upward movement under pressure, and a connection for releasing the bar so as to permit a downward movement of the bearing.

CARL WILLERS.
